US00D807385S

(12) **United States Design Patent** (10) Patent No.: **US D807,385 S**
 Olsen et al. (45) Date of Patent: ** Jan. 9, 2018

(54) **DISPLAY SCREEN OR PORTION THEREOF WITH GRAPHICAL USER INTERFACE**(71) Applicant: **Neurotrack Technologies, Inc.**, Redwood City, CA (US)(72) Inventors: **Daniel S. Olsen**, Redwood City, CA (US); **Caitlyn L. Krebs**, Redwood City, CA (US)(73) Assignee: **NEUROTRACK TECHNOLOGIES, INC.**, Redwood City, CA (US)(**) Term: **15 Years**(21) Appl. No.: **29/572,787**(22) Filed: **Jul. 29, 2016**(51) LOC (11) Cl. **14-04**

(52) U.S. Cl.

USPC ..... **D14/486**(58) **Field of Classification Search**USPC D14/485-495
CPC G06F 3/0482; G06F 3/0484; G06F 3/0485;
G06F 3/0486

Primary Examiner — Ian Simmons

Assistant Examiner — Shannon Morgan

(74) Attorney, Agent, or Firm — Richard T. Ogawa;
Ogawa P.C.(57) **CLAIM**

The ornamental design for a display screen or portion thereof with graphical user interface, as shown and described.

DESCRIPTION

The FIGURE is a front view of a display screen or portion thereof with graphical user interface showing our new design.

The broken lines in the FIGURE showing portions of the display screen and graphical user interface depict portions of the article that form no part of the claimed design.
